DENTAL MOUTH MIRROR

Alexander P. Preston, Denver, Colo.

Application August 2, 1938, Serial No. 222,728

1 Claim. (Cl. 306—28)

This invention relates to that classification in equipment and accessories particularly so-called dental mouth mirrors, the concept being such as to render its use practicable and feasible in any equivalent mouth mirror such as may be used in medical, surgical and dental work and in any other line of endeavor in which its employment is found proper.

The conventional construction employed for this purpose comprises a longitudinally elongated handle of appropriate shape and proportion, the same termination at the working end in a tapered shank carrying a laterally offset disk-like or equivalent shaped mirror. In some constructions the handle and shank are made as independent units and separably adjoined for mirror replacement purposes.

The present invention, specifically speaking, has for its object the provision of an assemblage wherein the shank and handle are sectional or adjoined in a one-piece formation, the shank being so constructed as to accommodate a bodily detachable and insertable mirror, whereby to facilitate replacement and to thereby materially minimize the expense incident to substituting a new mirror whenever necessary or desired.

More specifically, I have evolved and perfected a simple and economical replacement mirror and an adapter cup on the shank, there being remote controlled means for latching and maintaining the mirror unit in place.

Other features and advantages, classifiable as objects of the invention will become more readily apparent from the following description and the accompanying illustrative drawing.

In the drawing, wherein like numerals are employed to designate like parts throughout the various views:

Figure 1 is an elevational or what may be conveniently called a top plan or face view of the improved instrument as perfected in accordance with the principles of the present inventive conception.

Figure 2 is a view partly in section and partly in elevation, the portions being broken away to expose the internal mechanism forming the latch control device.

Figure 3 is an enlarged fragmentary end view of one end portion of the socketed handle discloses the button and associated features.

Figure 4 is an enlarged fragmentary longitudinal sectional view which may be said to be taken approximately on the plane of the line 4—4 of Figure 1.

Figure 5 is a top plan view of the latch

equipped accommodation cup for the renewable mirror unit.

Figure 6 is a sectional view of the hook equipped mirror holding frame or receptacle.

Figure 7 is a section on the line 7—7 of Figure 6.

Referring now to the drawing by distinguishing reference numerals, it will be observed that the assemblage, as a whole, is broadly characterized (in its preferred embodiment) by a main body or handle unit 8, there being separably attached to this a complementary shank unit 9, the shank unit 9 serving to accommodate the renewable mirror unit 10. At this point it is to be explained that it is not absolutely essential that the parts 8 and 9 be separate in view of the independent detachable mirror unit 10.

Specifically, the handle comprises a straight bar preferably polygonal in cross section, one end thereof being formed with a counterbore providing a pocket to accommodate a coiled spring 11. The main bore, which is much smaller in cross sectional dimension, serves to accommodate an adapter sleeve or tube 12, this being mounted for reciprocation in said bore. The finger controlled end of the sleeve 12 is attached to a push button 13, this being slidably mounted in the outer end of the socket. The coiled spring surrounds the sleeve and is contained in the socket and bears at one end against the closed end of the socket and at its opposite end against the button. The tension of the spring is such that it normally projects the button to the operating position depicted in the drawing.

Any suitable type of coupling or separable joint is employed at the point 14 to adjoin the detachable shank unit to the handle unit. Moreover, the shank unit is tapered and shaped as in any conventional dental mouth mirror. In the present instance, however, it is formed with a longitudinal bore registering with a bore in the handle. Then too, it is provided with a reinforced portion 15 carrying a circular shallow adapter cup or head 16 to accommodate the mirror unit 10. This unit comprises the mirror 17 and a metal adapter receptacle 18 integrally attached thereto. The receptacle 18 fits telescopically in the cup 16 and is provided on its bottom with spaced shanks or brackets 19 carrying retention hooks 20. The central portion of the cup 16 is recessed as at 21 and the cavity formation is such as to accommodate the bill portions of the retention hooks. Then too, there is sufficient clearance here provided to accommodate the T-shaped latch or detent 22 on the outer end of the push-pull wire 55

23. This wire, as is obvious, runs through the bore in the shank, through the adapter sleeve 12 and through a bore in the plug or button 13 where it is clenched as at 24 against the button 5 to provide the desired assemblage of features. The wire is sufficiently rigid to operate the latch and also sufficiently flexible to bend and conform itself to the crook portion or bend 25 of the shank. Normally the spring exerts pressure on the button and T-shaped latch to maintain the latch engaged releasably with the hooks 20. Consequently, the mirror unit is securely anchored in the accommodation cup 16. Thus, by turning the mirror down against a table or the like and pushing 10 on the button against the tension of the spring 11, it is obvious that the latch becomes released from the keeper or retention hooks 20 allowing the mirror to drop out so that it can be conveniently replaced. As will be seen in Figures 4 and 15 20 5 the recess or cavity 21 is provided with a deep part for receiving the hooks 20 with a shallower part in rear of the deep part so that when the member 22 is moved out of engagement with the hooks it will move into the shallow part and 25 thus the specific formation of the recess or cavity 21 will insure the member 22 always engaging the hooks 20.

In practice, the glass mirror is suitably cemented or otherwise anchored in the backing 30 frame or receptacle 18. Then too, the whole construction is of such material and the parts assembled with requisite precision to permit it to withstand intense moist heat for the purpose of sterilization, as is obvious.

35 Briefly and broadly, the inventive concept finds its foundation in a handle and shank assemblage wherein the replaceable mirror per se is detachably mounted for expeditious application and removal. Means other than the latch controlled

arrangement may of course come within the purview of this concept. So far as is known, however, it is new to employ an interchangeable standardized mirror and to in any way separably and operatively support the same on the handle 5 and shank means. The claim is presented accordingly.

It is thought that the description taken in connection with the drawing will enable a clear understanding of the invention to be had. Therefore, a more lengthy description is thought unnecessary.

While the preferred embodiment of the invention has been shown and described, it is to be understood that minor changes coming within 15 the field of invention claimed may be resorted to if desired.

I claim:

Means for fastening one member in a socket 20 in a second member comprising a pair of spaced hooks, each hook including a shank and a curved beak, one side of each shank being fastened to the bottom part of the first member with the beak extending downwardly from said bottom, the second member having a cavity therein opening out through the socket for receiving said hooks, said cavity having a deep part for receiving the beaks of the hooks and a shallow part receiving portions of the shanks, said shallow part having a bottom wall sloping upwardly from the deep part of the cavity to the end of the shallow part thereof and a slideable stem in the second member having a T-shaped head located in the cavity and engaging the hooks, said T-shaped head moving into the shallow part of the cavity 30 into contact with the sloping wall thereof when the stem is moved in a direction to move the head out of engagement with the hooks. 35
